BARREL LOCKING RING

Colin B. Dale, Oak Park, Ill., assignor to Cornell Securities Corporation, Cleveland, Ohio, a corporation of Delaware

Application February 2, 1940, Serial No. 316,996

5 Claims. (Cl. 220—61)

This invention relates to locking means for metallic receptacles or containers, and particularly to the type in which the cylindrical body portion is open at one end and is formed with a bead extending around its open end. A barrel or "drum" of this type is provided with a cover for its open end having a flange which fits within the bead and is bent to overhang it; then a grooved ring, split at one point in its circumference, is fitted over the bead and the overhanging portion of the flange, usually with a gasket interposed between the bead and flange, so that when the clamping ring is contracted in this position the cover is secured firmly to the barrel, forming a fluid-tight seal therefor.

One object of this invention is to provide a closing or clamping device, operable without the aid of tools for removably securing such a cover on a drum or barrel of the type indicated. Another object is to provide means for applying the closing or contracting force to the clamping ring in an efficient manner and without any appreciable tendency to distort the ring. A further object is to provide a clamping ring of the type indicated with contracting means which shall be rugged in construction, inexpensive to manufacture and simple to operate. Other objects and advantages of the invention will appear from the following description. The invention consists in certain features and elements of construction in combination, as herein shown and described and as indicated by the claims.

In the drawing:

Figure 1 is a top plan view of a barrel or receptacle with its cover secured thereon by means of a locking ring embodying this invention.

Figure 2 is an enlarged fragmentary section taken at the line 2—2 on Figure 1.

Figure 3 is a fragmentary plan view of the adjacent ends of the locking ring showing them in contracted or locked position and indicating the corresponding positions of the operating lever and link.

Figure 4 is a fragmentary plan view of the parts shown in Figure 3 but illustrating them with the locking lever released and with the ring expanded to allow removal of the cover.

Figure 5 is a fragmentary elevation taken as indicated by the arrows 5—5 on Figure 3.

Figure 6 is a fragmentary section on the same scale as Figure 2, taken as indicated at line 6—6 on Figure 3.

Figure 7 is a fragmentary section taken at line 7—7 on Figure 4 to indicate the clearance afforded for removal of the ring in open position.

In the accompanying drawing I have illustrated one embodiment of my invention as designed for application to a metallic shipping drum or barrel 1. The upper edge of the drum is rolled to form a bead 2 at the open end; and a cover 3 applied to this end, includes an upwardly extending flange 4 terminating in an outwardly projecting portion 5 which overhangs the bead 2 preferably with a gasket or packing strip 6, interposed, as shown in Figure 2. For locking this cover in place there is provided a channeled clamping ring 7 which is split transversely at one point in its circumference to allow its ends to be separated for expanding the ring and releasing the cover 3 or to be drawn together for contracting the ring around the bead 2 and thus clamping the flange 5 in sealing position thereon. The ends of the ring 7 are provided with inwardly extending lugs 8 and 9 which may be formed integrally with the ring, or welded thereto. A locking lever 10 is fulcrumed on the lug 8 and a pair of links 11 connect the lever with the lug 9 being secured against the upper and lower faces of the lever and the lug, as seen in Figure 5. The lever 10 is disposed on the under side of the lug 8.

In certain conventional constructions the fulcrum connection of the operating lever and the connection of the link to the lugs of the ring have been in the form of fixed pivots, but in that case, when the handle is swung to closing position, the pull exerted against the lugs is so much out of line with the ring itself that a considerable bending movement is set up at a distance back from each end of the ring where the lug connects with it. This tends to distort the end portions of the ring outwardly so that they are not effective in holding the cover tightly to the bead of the drum at that point, and under extreme tension the end portions of the ring, including the lugs, may even fail and break away, due to the excessive tension introduced by the bending forces.

The present invention overcomes these defects of conventional design by providing slots 12 and 13 in the lugs 8 and 9, respectively, which extend obliquely with relation to the circumference of the ring 7 and in converging relation outwardly thereof with respect to each other. The headed pin or loose rivet 14 by which the lever 10 is fulcrumed on the lug 8 engages in the slot 12 and a similar pin or rivet 15 connects the link 11 with the lug 9 by engagement in the slot 13. The slots 12 and 13 terminate outwardly, as close as possible to the flange 4 so that with

the pins 14 and 15 shifted to the outer ends of the slots, as shown in Figure 3, the closing tension applied to the ring is exerted as nearly as possible in line with the ring itself, and without any considerable bending moment to distort the ends of the ring. The oblique and converging relation of the slots 12 and 13 causes the pins 14 and 15 to be forced to the outer ends of these slots; and, preferably, the pins are formed with enlarged heads 14^a and 15^a respectively, which are thus forced into contact with the vertical flange 4 of the cover 3. The tension exerted on the ring 7 when the lever 10 is swung to closing position is thus accompanied automatically by a force which crowds the heads 14^a and 15^a against the inner face of the flange 4 at points close to the extreme ends of the ring 7 so as to draw these end portions snugly in place against the bead 2 and within the normal circumferential outline of the ring 7. In other words, the bending moments which are present in the conventional structure, and tend to distort the ends of the ring, are not only eliminated by the sliding of the pins 14 and 15 in the closing action, but this shifting movement is itself employed to cause the ends of the ring to hug the bead of the barrel instead of being sprung away from it as in former designs.

When the lever 10 is swung to open position, as shown in Figure 4, the ends of the ring 7 are separated, and the ring is expanded to allow its removal so as to free the cover 3 from the drum. The separating action applied to the pins 14 and 15 by this movement of the lever 10 shifts them slidably in their slots 12 and 13 toward the diverging inner ends of the slots, thus causing the enlarged heads 14^a and 15^a to travel away from the channel of the ring 7 and providing clearance between these heads and the lower edge 7^a of the channel, which permits the ring to be lifted clear of the bead 2. The dimension of this clearance is indicated at A on Figure 7. Similarly, this clearance will be available in placing the ring in position to secure the cover in sealed relation on the barrel or drum.

From the foregoing it will be seen that I have devised a locking ring which is as economical to manufacture as previous conventional designs, but which utilizes more efficiently the force applied for drawing the ring into locking position and which avoids certain strain and distortion of the parts inherent in prior structures. While there is shown and described herein certain specific structure embodying the invention, it will be manifest to those skilled in the art that various modifications and rearrangements of the parts may be made without departing from the spirit and scope of the invention, and that the same is not limited to the particular form herein shown and described, except in so far as indicated by the appended claims.

I claim:

1. In a locking device for a metallic receptacle having a bead formed about its open end and a cover having a flange fitting over the head, a 65 contractible channeled clamping ring having portions engaging the bead and cover flange to press the same together when the ring is contracted, and means for contracting the ring including a lever fulcrumed on one end portion of the ring and a link connecting said lever with the other end portion of the ring, the fulcrum of the lever and the connection of the link with the ring comprising pivots 70 slidably in slots formed respectively in said end portions of the

ring, said slots extending obliquely with relation to the circumference of the ring and converging toward it, said pivots having portions extending into a plane which intersects the flange of the cover and dimensioned to bear against said flange when the ring is contracted with said pivots at the outer end portions of the slots.

2. A split locking ring for the purpose indicated having an inwardly open channel cross-section, the adjacent end portions of said ring being provided with inwardly extending lugs, said lugs having slots formed respectively therein and extending obliquely with relation to the circumference of the ring and converging toward it, and means for contracting said ring comprising a lever fulcrumed on one of said lugs and a link connecting said lever with the other lug of the ring, the fulcrum of the lever and the connection of the link to said lugs respectively comprising pins 20 slidable outwardly in the slots when the lever is operated to contract the ring, the outer ends of the slots extending substantially to the circle of the inner circumference of the ring whereby the final contractile tension of the lever and link is applied to the ring substantially in line therewith.

3. In combination with a metallic receptacle having a bead formed about its open end and a cover having a flange fitting into said open end and over said bead, a contractible channeled locking ring formed to engage the bead and cover flange for pressing the same together when the ring is contracted around them, said ring being split transversely at one point in its circumference and having inwardly extending lugs on its adjacent end portions, said lugs having slots formed respectively therein extending obliquely with relation to the circumference of the ring and converging toward it, and means for contracting said ring comprising a lever fulcrumed on one of said lugs and a link connecting said lever with the other lug of the ring, the fulcrum of the lever and the connection of the link to said lugs respectively comprising pins 35 slidable outwardly in the slots when the lever is operated to contract the ring, the outer ends of the slots being disposed closely adjacent the outlines of the ring, and said pins having head portions extending into a plane which intersects the flange of the cover and dimensioned to bear against said flange when the pins are shifted toward the outer ends of the slots as the ring is contracted by operation of the lever.

4. In a locking device for a metallic receptacle having a bead formed about its open end and a cover having a flange fitting over the head, a contractible channeled clamping ring having portions engaging the bead and cover flange to press the same together when the ring is contracted, and means for contracting the ring including a lever fulcrumed on one end portion of the ring and a link connecting said lever with the other end portion of the ring, guiding means on said end portions of the ring by which the fulcrum of the lever and the connection of the link with the ring are both shifted in directions oblique to the circumference of the ring and converging outwardly with respect thereto by operation of the lever in contracting the ring, and means carried respectively by the fulcrumed end of the lever and the end of the link which is connected to the ring, said last mentioned means projecting into a plane which intersects the flange of the cover and being dimensioned to bear against said flange when

the lever fulcrum and the link connection are moved outwardly by operation of the lever.

5. A split locking ring for the purpose indicated having an inwardly open channel cross-section, the adjacent end portions of said ring being provided with inwardly extending lugs, said lugs having slots formed respectively therein and extending obliquely with relation to the circumference of the ring and converging toward it, and means for contracting said ring comprising a lever fulcrumed on one of said lugs and a link connecting said lever with the other lug of the ring, the fulcrum of the lever and the con-

nection of the link to said lugs respectively comprising pins slidable outwardly in the slots when the lever is operated to contract the ring, the outer ends of the slots extending substantially to the circle of the inner circumference of the ring whereby the final contractile tension of the lever and link is applied to the ring substantially in line therewith, the center lines of said slots, if extended outwardly, converging to a point in the ring and between the ends thereof as the ring reaches its final contracted position.

10 COLIN B. DALE.

CERTIFICATE OF CORRECTION.

Patent No. 2,257,039.

September 23, 1941.

COLIN B. DALE.

It is hereby certified that error appears in the printed specification of the above numbered patent requiring correction as follows: Page 1, first column, line 26, for "inexepnsive" read --inexpensive--; page 2, first column, line 65, claim 1, for the word "head" read --bead--; and that the said Letters Patent should be read with this correction therein that the same may conform to the record of the case in the Patent Office.

Signed and sealed this 4th day of November, A. D. 1941.
